TYPEWRITER STOP MECHANISM

James F. Koca, Woodstock, Ill., assignor to Woodstock Typewriter Company, Woodstock, Ill., a corporation of Illinois

Application July 13, 1940, Serial No. 345,266

14 Claims. (Cl. 197—176)

This invention relates to typewriters in general, and particularly to certain operating mechanism therefor. More specifically, the invention relates to mechanism to set tabulator stops by depressing a set key whereby depression of the tabulator key will permit movement of the carriage up to a set stop.

The present invention is an improvement of the mechanism disclosed and claimed in applicant's Patent No. 2,153,630, granted April 11, 1939, for Stop mechanism for typewriters.

An object of the invention is the provision of new and improved mechanism operated by a tabulator set key to set stops in pre-selected positions to stop the movement of the typewriter carriage at a precise position when the tabulator key is operated.

Another object of the invention is the provision of new and novel means controlled by the depression of a stop set key to shift a stop from a normal inoperative position to an operative position so as to engage a stop member, the positioning of which is controlled by mechanism operatively associated with tabulator key lever means and brought into operation by the depression of a tabulator key.

A further object of the invention resides in the provision of improved stop set mechanism and tabulator mechanism correlated and cooperating to effect accurate positioning of the stops and the bringing into position of a stop member whereby margins or columns may be selected in advance by the mere manipulation of a stop key and the carriage caused to assume the proper stopping position by a stop when a tabulator key is depressed.

A still further object of the invention is the provision of elements constructed and arranged to impart the greatest efficiency with the greatest ease and the utilization of few and simple parts, the parts and assembly thereof being characterized in that the necessary elements of the stop set mechanism, the tabulator mechanism and the escapement mechanism are brought into play at precisely the proper time to effect proper and accurate positioning of the carriage.

Numerous other objects and advantages will be apparent throughout the progress of the following specification.

The accompanying drawings illustrate a selected embodiment of the invention and the views therein are as follows:

Fig. 1 is a detail rear elevational view of a typewriter and embodying the invention;

Fig. 2 is a detail elevational view, partly in section, of the left hand side of the typewriter;

Fig. 3 is a detail perspective view of certain mechanism controlled by the tabulator mechanism;

Fig. 4 is a detail view similar to Fig. 3 but including some of the stop setting mechanism;

Fig. 5 is a detail elevational view partly in section of the right hand side of the typewriter; and

Figs. 6 and 7 are detail sectional views on the lines 6—6 and 7—7 of Fig. 1.

The mechanism herein shown to illustrate the present invention is shown applied to the popular well-known Woodstock typewriter, although the invention is susceptible of use on other makes of machines. The typewriter frame 1, Figs. 2 and 5, has the usual platen 2 mounted on the carriage frame 3, which is slidably arranged between opposed ways 4. An escapement bar 5, Fig. 1, is

15 pivotally supported in any known manner on a part of the carriage frame 3 and has normal meshing engagement with a pinion 6 which is controlled by an escapement or ratchet wheel 7. The escapement or ratchet wheel 7, and its manner of operation, are disclosed in pending applications Serial No. 332,787, filed May 1, 1940, which matured as Patent No. 2,286,403, June 16, 1942, and Serial No. 332,789, filed May 1, 1940, which matured as Patent No. 2,286,404, June 16, 1942.

20 The construction and operation of the escapement bar, the ratchet wheel, and cooperating mechanism form no part of the present invention except insofar as the same may be necessarily incorporated in connection with other operable mechanism. The escapement bar 5, pinion 6 and escapement or ratchet wheel 7 are for the usual purpose of holding the carriage in a predetermined position against the urging action of the usual resilient or spring means R which moves the carriage in a predetermined direction when a key is depressed.

25 A pivotally suspended slotted bar 8 is arranged above and slightly to the rear of the escapement bar 5 and this bar has a plurality of slots 9 spaced apart a distance equal to a letter space. The slotted bar 8 is adapted to receive in the slots 9 thereof the stops 10 which are pivotally mounted on a circular bar 11 arranged immediately forward of the slotted bar 8. A second slotted bar

30 45 50 55

The slotted bar 8 is adapted to guide and receive the stops 10 on the bar 11 and support them in either operative or

inoperative position depending upon the position at which they are set. There are as many stops 10 as there are slots 9 and 13 in the bars 8 and 12 respectively so that the carriage may be stopped at any desired position intermediate the length of travel of the carriage. The slotted bars 8 and 12, the circular bar 11, and the stops 10 may be of the kind disclosed in applicant's aforesaid Patent No. 2,153,630. Also, as disclosed in said patent, the pivoted slotted bar 8 may be provided with a finger piece 14, to oscillate the bar 8 to clear all stops 10 which are in a down position, moving them to their upper normal inoperative non-stop position. The oscillatory movement of the bar 8 is limited by suitable stops, there 15 being a spring provided to hold normally the slotted stop bar 8 in its normal suspended position as shown in the drawings.

The stops 10 are for the purpose of stopping accurately the carriage at any desired position, 20 making it convenient for the typist to position properly lines, margins or columns. The stops are positioned in the slots 9 by stop depressing mechanism controlled by the depression of a separate stop set key 15. The stops 10 hold the 25 carriage in position and prevent the carriage from being moved to the left by the resilient means R until the carriage is released by operation of the escapement mechanism.

The stop depressing mechanism comprises the stop set key 15 on the key lever 16 which is preferably positioned at the left hand side of the key board near the upper part thereof. The key lever 16, Fig. 2, is pivotally mounted at 17 on a part of the typewriter frame and includes an upwardly extending integral portion 18 provided with an enlargement 19. The enlargement 19 has a slot 20, through which slot a pin 21 on the frame extends to guide the movement of the key lever 16 as well as to limit its movement. A link 22, adjustable at 23, Fig. 2, has one end pivoted at 24 to the upper end of the part 18 of key lever 16 and its other end pivoted at 25 to an arm 26 rigid with a shaft or rod 27. The shaft or rod 27 extends between the arms 28 of a bracket 29 rigidly secured to a part of the typewriter frame. The shaft or rod 27 is revolvably mounted in the arms 28 and is held against axial movement by the rigid connection of the arm 26 on one end and by a crank arm 30 rigidly connected to the other end, Fig. 4.

A link 31 is pivotally connected at 32 to the crank arm 30 and extends upwardly and vertically from the crank arm, passing through a slot 33, Fig. 2, formed in the frame. The link 31 has a slot 34 formed therein through which a set screw 35 passes to slidably mount the link 31 on a rigid upstanding support 36 formed on the frame. The link 31 includes a finger 37 made integral therewith and turned inwardly as shown in several figures so as to be in position to cooperate with the several stops 10. The depression of the key 15 will move the finger 37 downwardly to depress or move a selected stop downwardly for cooperation with the escapement mechanism to stop the carriage at the position in which a stop 10 has been set by pre-selection. A spring is fastened to the arm 30, Fig. 4, and to a fixed member to hold the finger 37 in its normal raised position.

The stop setting mechanism cooperates with the escapement mechanism in that the escapement mechanism releases the carriage from a pre-selected stop whereupon the resilient means R moves the carriage to the left (to the right look-

ing at Fig. 1). The release of the escapement mechanism is accomplished by the depression of a tabulator key 38, Fig. 5, which is mounted on the tabulator key lever 39. The key lever 39 is guided at the front of the machine by a comb (not shown) and is pivoted at 40a to a part 40 on the frame. The other typewriter keys also are mounted on said part. A spring 41 may be provided beneath the key lever 39, Fig. 5, to hold the key lever 39 in its normal upward position and to return the key to its up position after having been depressed. A link 42 has one of its ends pivotally connected at 43 to the tabulator key lever 39 and its other end pivotally connected at 44 to one end of a rocker bar 45 which is pivoted intermediate its ends at 46 to a part of the typewriter frame, Fig. 1. The construction, arrangements and connections are such that the depression of the tabulator key 38 will rock the lever 45 on its pivot 46 and raise the end 47 thereof upwardly. The end 47 of the rocker lever or bar 45, Fig. 1, carries a shoe 48 which underlies the toothed escapement bar 5, and its purpose is to shift or move the escapement bar on its pivot and move the teeth of the escapement bar out of meshing relationship with the pinion 6, whereby the carriage is free to be moved to the left (to the right, Fig. 1) by the resilient means to the end of its travel or until another pre-selected stop 10 is encountered.

The depression of the tabulator key 38 also brings into operation a stop member 49 which is adapted to be engaged by a stop 10 when the carriage is moving to the left (to the right, Fig. 1). This stop member 49 is moved into the path of the stops 10 on the carriage and remains in stopping position so long as the tabulator key 38 is held depressed. When the tabulator key is released the shoe 48 will return to inoperative position to permit engagement again of the teeth on the escapement bar 5 with the pinion 6, after which time the stop member 49 will be retracted and removed from position.

The stop member 49, Fig. 1, may comprise an integral part or arm of a bracket 50 which is pivotally mounted on a shaft 51 having one end thereof mounted in the support 36 and its other end mounted in a support 52 preferably formed integral with the frame, Fig. 1. A spring 53 surrounds the shaft 51 and tends to urge the bracket 50 towards the support 52. A link 54 has its upper end pivotally connected at 55 to an arm of the bracket 50 and its lower end pivotally connected at 56 to an arm 57 which in turn is pivotally connected at 58 to an arm 59 of a bracket member 60, Figs. 3, 4 and 5. The end of the arm 57 extends a predetermined distance beyond the pivot 58, there being an ear 61 formed on the end of the arm 57 and overlying the arm 59 of the bracket member 60, Fig. 4. A spring 62 is attached to the ear 61 and holds arm 57 resiliently and operatively, Fig. 3. This spring 62 also tends to return the stop member 49 to inoperative position and assists in so maintaining it. A link 63 has its lower end pivoted at 58, Figs. 3 and 4, and its upper end pivotally connected at 64 to the arm 47 of lever 45, Figs. 1, 2 and 5. A spring 63' is connected to the link 63, Figs. 3 and 4, and to a rigid part on the frame to hold the stop member 49 in its normal inoperative position. The stop member 49 is moved to operative position through the construction just described when the tabulator key 38 is depressed. Upon the depression of said key 38, downward movement of the link 42

transmitted thereto by the key lever 39 raises the arm 47 of the lever 45 and raises the link 63, causing upward movement of the arm 59 of the bracket member 60. Inasmuch as the link 54 is pivotally connected to the arm 59, the link 54 will likewise be raised. As the link 54 rises, the bracket member 50 carrying the stop member 49 will be swung on its pivot causing the stop member 49 to lie in the path of one of the several stops 10 which have previously been positioned. The depression of the key 38 likewise causes the shoe 48 to be raised thereby releasing the escapement mechanism and permitting the resilient means R to move the carriage to the left (to the right, Fig. 1) until it engages the first selected stop 10. Release of the key 38 again throws in the escapement mechanism whereby the carriage is stopped. The release of the key 38 likewise causes the stop member 49 to be retracted from the path of the stops, allowing the carriage again to be operated one letter space at a time as usual.

When a stop 10 strikes the stop member 49 there may occur a rebound or back-lash, even though it be of a limited extent. To overcome any back-lash or rebound a finger 65 is provided to engage the opposite side of a stop 10, Figs. 6 and 7. This finger 65 is pivotally mounted on the same shaft 51 upon which the bracket member 50 carrying the stop member 49 is mounted, Fig. 7. This rebound finger has a slot 66 through which there extends a pin 67 attached to the stop member 49, thereby providing for limited pivotal movement sufficient to effect proper operation. A spring 68, Fig. 7, is secured to the finger 65 and to a part on the bracket 50 to hold the finger 65 toward the forward end of the slot. The finger 65 has a beveled surface 69 to allow a stop 10 to kick the finger 65 away from the stop 10 until the stop 10 reaches the stop member 49. As soon as the finger 65 has been pushed outwardly by the engagement therewith of a stop 10, the spring 68 immediately pulls the finger 65 to normal position at practically the same instant the stop 10 strikes the stop member 49. The stop 10 will, therefore, be positioned between the two members 49 and 65. The carriage cannot advance because a stop 10 is engaged by the stop member 49 and it cannot reverse its operation, by rebound or otherwise, because of the position of the finger 65. The carriage therefore is caused to stop at the precise position desired.

A stop plate 70, Fig. 1, preferably having its face provided with resilient material, is secured to the bracket 50, and its purpose is to limit the movement of the stop member 49 and the finger 65 because of the engagement of the plate 70 with the lower part of the bar 8 in which the stops 10 are pre-selected positioned.

Operation

A key 15 is depressed to position a stop 10 to a desired pre-selected position, the stop 10 being set at the position assumed or occupied by the carriage so that the carriage will be stopped at that same precise position when the tabulator key is depressed. If more than one stop 10 is positioned the carriage will stop at those points progressively when the tabulator key is depressed between the positions defined by the positions of the stops. When a key 15 is depressed motion is transmitted from the key lever 15 through the arm 26, shaft 27 and then through the arm 30 to the link 31 and its finger 37. The finger 37 then moves a stop 10 downwardly into stop position in a slot 9 in the bar 8. As many stops 10 as

are necessary may be so set. Depression of the tabulator key 38 transmits motion through the key lever 39, the lever 45, link 63, and link 54 to the bracket 50 upon which the stop member 49 is secured to bring the stop member 49 into position properly to be engaged by a stop 10 on the moving carriage. Depression of the key 38 also operates the shoe 48 because of its attachment to the part 47 of lever 45. The shoe 48 shifts the escapement bar 5 to release it from its pinion 6 whereupon the resilient means R pull the carriage until a stop 10 strikes the stop member 49. Just immediately prior to the time the stop member 49 is contacted by a stop 10 on the moving carriage, the rebound finger 65 is shifted out of the path because of the engagement of a stop 10 with the bevelled surface 69 on the finger 65. Immediately after the stop 10 passes the finger 65 and just about the time the stop 10 engages the stop member 49, the finger 65 is moved back into normal position so as to lie on the rear side of the just passed stop 10. The stop 10 is therefore positioned between the stop member 49 and the rebound finger 65 whereby the carriage is maintained stationary at the exact precise position, at which position it remains until the tabulator key is released when it will move forward, to the left (to the right, Fig. 1) a distance just sufficient to clear the stop member 49. The release of the tabulator key 38 causes the escapement bar 5 to be released by the shoe 48 and again become meshed with the pinion 6. The release and return to normal position of the stop member 49, and the return of the escapement bar 5 into meshing relation with the pinion 6, provide the aforesaid forward movement of the carriage a distance only sufficient to clear the said stop so as not to be in the way should the tabulator key be operated again. Of course, immediately after the tabulator key is released the stop member is shifted from stopping position so that the typewriter may be operated without hindrance by the stop member 49.

The invention provides new and novel means to set effectively any number of stops 10 as may be required by the mere depression of a set key provided for that purpose. Moreover, the invention provides new and improved means for causing operation of the stop member to stop the carriage at a particular position when the tabulator key is depressed. Also, the operation of the escapement mechanism is synchronized and correlated with the tabulator mechanism to assure accurate and positive operation. The parts are few and simple and provide for accurate and efficient operation.

Changes may be made in the form, construction and arrangement of the parts without departing from the spirit of the invention or sacrificing any of its advantages, and the right is hereby reserved to make all such changes as fairly fall within the scope of the following claims.

I claim:

1. A typewriter comprising a shiftable carriage, tabulator stops carried by said carriage, a counter-stop supporting member pivotally mounted on a part of the typewriter frame for forward and rearward movement towards and away from said carriage, a counter-stop member rigid with said supporting member, means controlled by the depression of a key to swing said counter-stop supporting member on its pivot to bring the counter-stop member into tabulator position to engage a stop, a rebound finger pivoted on the typewriter frame adjacent the counter-

stop member to prevent rebound of the carriage after a tabulator stop has engaged the counter-stop member, and resilient means interposed between said counter-stop supporting member and the typewriter frame for absorbing shock upon engagement of a tabulator stop with the counter-stop member.

2. A typewriter comprising a shiftable carriage, tabulator stops carried by said carriage, a shaft mounted on the typewriter frame and extending substantially parallel with the direction of shiftable carriage movement, a counter-stop member pivotally mounted on said shaft for forward and rearward movement towards and away from said carriage, key controlled means for swinging said counter-stop member on its pivot to bring the counter-stop member into tabulator position to engage a tabulator stop, resilient means arranged on said shaft in cooperative relation with said counterstop member and the typewriter frame for absorbing shock upon engagement of the tabulator stop with the counter stop member, and a resiliently urged rebound finger pivotally mounted on said shaft adjacent said counter-stop member, the parts being so conformed and arranged to operate whereby said key control means may be operated to cause said counter stop member to engage a tabulator stop and thereby arrest operative movement of the carriage at the precise position of said tabulator stop and to cause said rebound finger to prevent rebound of the carriage after a tabulator stop has engaged the counter-stop member.

3. A typewriter comprising a shiftable carriage, tabulator stops carried by said carriage, a shaft mounted on the typewriter frame and extending substantially parallel with the direction of shiftable carriage movement, a counter-stop member pivotally mounted on said shaft for forward and rearward movement towards and away from said carriage, key controlled means for swinging said counter-stop member on its pivot to bring the counter-stop member into tabulator position to engage a stop, a rebound finger pivotally mounted on said shaft adjacent said counter-stop member to prevent rebound of the carriage after a tabulator stop has engaged the counter-stop member, and spring means for yieldably holding said rebound finger forwardly with respect to said counter-stop member.

4. A typewriter comprising a shiftable carriage, tabulator stops carried by said carriage, a shaft mounted on the typewriter frame and extending substantially parallel with the direction of shiftable carriage movement, a counter-stop member pivotally mounted on said shaft for forward and rearward movement towards and away from said carriage, key controlled means for swinging said counter-stop member on its pivot to bring the counter-stop member into tabulator position to engage a stop, a rebound finger pivotally mounted on said shaft adjacent said counter-stop member to prevent rebound of the carriage after a tabulator stop has engaged the counter-stop member, spring means for yieldably holding said rebound finger forwardly with respect to said counter-stop member, and pin and slot means cooperative between said counter-stop member and said rebound finger for limiting movement of the rebound finger.

5. A typewriter comprising a shiftable carriage, tabulator stops carried by said carriage, a shaft mounted on the typewriter frame and extending substantially parallel with the direction of shiftable carriage movement, a counter-

stop member pivotally mounted on said shaft for forward and rearward movement towards and away from said carriage, key controlled means for swinging said counter-stop member on its pivot to bring the counter-stop member into tabulator position to engage a stop, a rebound finger pivotally mounted on said shaft adjacent said counter-stop member to prevent rebound of the carriage after a tabulator stop has engaged the counter-stop member, spring means for yieldably holding said rebound finger forwardly with respect to said counter-stop member, and a cam surface on the forwardly extending portion of said rebound finger for moving the finger about its pivot upon initial engagement with a tabulator stop.

6. A typewriter comprising a shiftable carriage, tabulator stops carried by said carriage and movable from inoperative to operative position, a slotted bar for receiving said tabulator stops when moved into operative position, a shaft mounted on the typewriter frame and extending substantially parallel with the direction of shiftable carriage movement, a counter-stop member pivotally mounted on said shaft for forward and rearward movement towards and away from said carriage, key controlled means for swinging said counter-stop member on its pivot to bring the counter-stop member into tabulator position to engage a stop, and means carried by said counter-stop member for engaging said slotted bar to limit movement of the counter-stop member towards said carriage.

7. A typewriter comprising a shiftable carriage, tabulator stops carried by said carriage and movable from inoperative to operative position, a slotted bar for receiving said tabulator stops when moved into operative position, a shaft mounted on the typewriter frame and extending substantially parallel with the direction of shiftable carriage movement, a counter-stop member pivotally mounted on said shaft for forward and rearward movement towards and away from said carriage, key controlled means for swinging said counter-stop member on its pivot to bring the counter-stop member into tabulator position to engage a stop, a rebound finger pivotally mounted on said shaft adjacent said counter-stop member to prevent rebound of the carriage after a tabulator stop has engaged the counter-stop member, and means carried by said counter-stop member for engaging said slotted bar to limit movement of the counter-stop member and said rebound finger towards said carriage.

8. Tabulator mechanism for typewriters comprising an escapement rack, a lever pivotally mounted adjacent said rack for lifting the rack, key operated means for operating said lever, an arm pivotally mounted on the typewriter frame, a second arm pivotally mounted on said first arm and having a portion overlying the first arm to effect upward movement of the second arm upon upward movement of the first arm, a counter-stop member movable between operative and inoperative positions with respect to a carriage, linkage mechanism interconnecting said lever and said first arm for moving the arm upwardly upon operation of the lever, linkage mechanism interconnecting said second arm and said counter-stop member for operating the member, and return spring means connected to said overlying portion of the second arm.

9. Tabulator mechanism for typewriters comprising an escapement rack, a lever pivotally mounted adjacent said rack for lifting the rack,

key operated means for operating said lever, an arm pivotally mounted on the typewriter frame, a second arm pivotally mounted on said first arm and having a portion overlying the first arm to effect upward movement of the second arm upon upward movement of the first arm, a counter-stop member movable between operative and inoperative positions with respect to a carriage, linkage mechanism interconnecting said lever and said first arm for moving the arm upwardly upon operation of the lever, linkage mechanism interconnecting said second arm and said counter-stop member for operating the member, return spring means connected to said overlying portion of the second arm, and return spring means separately connected to said first named linkage mechanism.

10. In a typewriter, tabulator stop mechanism comprising a bracket, an arm pivotally mounted on said bracket, a second arm pivotally mounted on said first arm and having a portion adapted to engage the first arm to effect movement of the second arm upon movement of the first arm in a predetermined direction, a counter-stop member, key operated means for moving said first named arm in said predetermined direction, linkage mechanism operatively connecting said second arm to said counter-stop member, return spring means operatively connected to said first arm, and separate return spring means operatively connected to said second arm.

11. A typewriter comprising a shiftable carriage, tabulator stops carried by said carriage, a shaft mounted on the typewriter frame and extending substantially parallel with the direction of shiftable carriage movement, a counter-stop member loosely mounted on said shaft and pivoted thereon for movement towards and away from said carriage, key controlled means for swinging said counter-stop member on its pivot to bring the counter-stop member into tabulator position to engage a stop, resilient shock absorbing means normally urging said loosely mounted counter-stop member to a predetermined stop position along the length of said shaft, and a resiliently urged rebound finger pivotally mounted on said shaft adjacent said counter-stop member to prevent rebound of the carriage after a tabulator stop has engaged the counter-stop member.

12. A typewriter comprising a shiftable carriage, tabulator stops carried by said carriage, a shaft mounted on the typewriter frame and extending substantially parallel with the direc-

tion of shiftable carriage movement, a counter-stop member loosely mounted on said shaft and pivoted thereon for movement towards and away from said carriage, key controlled means for swinging said counter-stop member on its pivot to bring the counter-stop member into tabulator position to engage a stop, spring means interposed between said shaft and said counter-stop member for absorbing shock upon engagement of a tabulator stop with the counter-stop member, a rebound finger pivotally mounted on said shaft adjacent said counter-stop member to prevent rebound of the carriage after a tabulator stop has engaged the counter-stop member, and spring means for yieldably holding said rebound finger forwardly with respect to said counter-stop member.

13. Tabulator mechanism for typewriters comprising an escapement rack, key operated means for lifting said rack, an arm pivotally mounted on the typewriter frame, a second arm pivotally mounted on said first arm and having a portion overlying the first arm to effect upward movement of the second arm upon upward movement of the first arm, a counter-stop member movable between operative and inoperative positions with respect to a carriage, linkage mechanism interconnecting said rack lifting means and said first arm for moving the arm upwardly upon operation of the lifting means, linkage mechanism interconnecting said second arm and said counter-stop member for operating the member, and return spring means connected to said overlying portion of the second arm.

14. Tabulator mechanism for typewriters comprising an escapement rack, key operated means for lifting said rack, an arm pivotally mounted on the typewriter frame, a second arm pivotally mounted on said first arm and having a portion overlying the first arm to effect upward movement of the second arm upon upward movement of the first arm, a counter-stop member movable between operative and inoperative positions with respect to a carriage, linkage mechanism interconnecting said rack lifting means and said first arm for moving the arm upwardly upon operation of the lifting means, linkage mechanism interconnecting said second arm and said counter-stop member for operating the member, return spring means connected to said overlying portion of the second arm, and return spring means separately connected to said first named linkage mechanism.

JAMES F. KOCA.
